UNITED STATES PATENT OFFICE

2,607,635

TRANSPORTATION OF GRANULAR SOLIDS

Reyner Kollgaard, Media, Pa., assignor to Houdry Process Corporation, Wilmington, Del., a corporation of Delaware

Application September 13, 1950, Serial No. 184,545

5 Claims. (Cl. 302—17)

1

The present invention relates to cyclic processes or systems in which solid particles or granules of contact material circulate through a downflow path wherein they pass through a process zone and are contacted with fluid and are thereafter elevated through an upflow path for return through the downflow path. The present invention is more particularly concerned with the upflow path wherein the particles are elevated, conveyed or transported through a vertically elongated laterally confined lifting zone or conduit by a lifting fluid or gas.

Such processes or systems, which are particularly adapted to the requirements of the chemical and oil refining industries, have a wide range of usefulness. Thus the granular contact material may be a porous or fused solid and may comprise or consist of a catalyst or catalytically inert material, the latter being used for heat exchange, or for the adsorption or fractionation of gases. The granular contact material can be advantageously in the form of relatively large particles or granules such as molded pellets, formed spheres and the like ranging in size from 0.05 to 0.5 inch in diameter, which, wholly or in part, gravitate through process zones as compact downwardly moving non-turbulent beds in a manner known to the art.

It has been found advantageous to transport the granular contact material for recirculation through the process zones of such systems by a pneumatic or gas lift which provides an upflow path. The system may comprise a single downflow path in which there are several process zones at different heights, through which zones the contact material flows consecutively so that the solid particles need be transported by the gas lift only once in a complete cycle of operation, or the system may comprise a plurality of gas lifts and/or downflow paths, each downflow path containing a single process zone. An exemplary system of the former type has been described in an article entitled "Houdriflow: New Design in Catalytic Cracking," appearing in the "Oil and Gas Journal," page 78, January 13, 1949.

In such systems, the use of a gas lift for the elevation of the granular contact material, instead of the mechanical elevators formerly employed, produces many advantages both as to control of the processing variables (operating conditions) and as to efficiency of operation (including cost and maintenance) but, at the same time, creates new problems. One of the chief problems in the operation of gas lifts of the type referred to herein is that of achieving simul-

2

taneously a high rate of circulation of solid particles and easy and rapid return of solid particles from the upflow path to the downflow path, while maintaining a low rate of attrition or breakage of the solid particles during such return.

The methods and apparatus disclosed in the prior art for effecting the necessary reversal of flow of the particles from the upflow path to the downflow path produce high attrition of the particles and/or necessitate the use of bulky and expensive equipment. Thus, when the lift is operated at high rates of circulation and at desirably low concentrations, the particles passing therethrough are traveling at such high velocities as they emerge from the lift that a considerable distance is required for the particles to change their upward movement to downward movement due to the decelerating effect of gravity. Consequently, the vessel or zone surrounding the top of the lift must be tall (such a vessel is commonly referred to as the disengaging vessel, hopper or zone, since it can be and frequently is used for disengaging lifting gas from solid particles). Because the disengaging vessel is necessarily at the top of the gas lift, which may be from 100 to 200 or more feet high, the problems and expense of supporting and bracing it at such a height are multiplied as the height of the vessel increases. Consequently, the reduced height of disengaging vessels made possible by the present invention, as described below, results in considerable savings in the cost of construction of the supporting structure.

An additional difficulty is encountered in commercial applications of gas lifts which involve the transfer of very large amounts of contact material, such as from 100 to 400 tons an hour, and need a gas lift pipe that is relatively wide, such as from 10 to 24 inches or more. A jet action occurs at the discharge end of the lift (i. e., the stream of particles emerging from the lift does not immediately dissipate or fountain into the surrounding relatively more extensive disengaging hopper but continues as a jet). Because the extent of the jet action (i. e., the height of rise of particles above the top of the lift due to jet action) is a function of the diameter of the lift path or conduit, additional disengaging height is necessary as the diameter of the lift pipe increases (for the same linear velocity of the particles discharging from the gas lift). Another effect that occurs under some conditions with gas lift pipes of relatively large diameter is a "mushroom" effect in which the

emergent particles, instead of fountaining or spraying outwardly and settling in the disengaging zone, form a relatively dense cloud or mass of particles suspended above the lift. Obviously, collision of the particles emerging from the lift with those in the cloud leads to undesirable attrition.

In accordance with the present invention, the undesirable effects noted above are minimized and/or overcome in systems of the type here involved, by passing a stream of lifting gas and particles moving at substantial velocity upwardly along the lower part of the vertical extent of a vertically elongated laterally confined lifting zone or conduit, flowing only portions of said stream radially outward, while passing said stream generally upward along the upper part of the lifting zone. Such flow can be achieved by using a lift or conduit having a plurality of vertically elongated radial projections spaced around the periphery of the conduit, which projections are in communication with the conduit and taper outwardly along their vertical extents to the top of the conduit. The stream of particles and gas, including the radially disposed portions, is discharged from the upper end of the lifting zone or conduit into a gas-solid disengaging zone or hopper having a considerably greater horizontal cross sectional area than that at the top of the lifting zone or conduit. Under the described conditions of operation, the horizontal area circumscribing the top of the lifting zone or conduit is substantially greater than the horizontal area at the top of the lifting zone or conduit through which the stream of gas and particles flow. As a consequence of this relationship, the stream of particles and gas is dispersed or spread over a greater area than its flow area before the stream enters the disengaging zone with the result that subsequent disengagement and free settling of the particles is simpler and attrition between the particles tends to be reduced.

The invention is especially applicable to systems involving the catalytic conversion of petroleum, and for the purpose of illustrating the invention, it will be described hereinafter in connection with a catalytic cracking system for the conversion of high boiling hydrocarbons to motor gasoline. Such a system is set forth in detail below in connection with the description of the drawings in which:

Figure 1 is a schematic generalized elevation of a typical system in which the present invention may be used.

Figures 2 and 3 are enlarged views of an embodiment of the present invention to be used as the upper portion of a gas lift in the system shown in Figure 1, Figure 2 being an elevation partially in section along the lines 2-2 in Figure 3, and Figure 3 being a top view;

Figure 4 is the top view of a modification of the embodiment of the invention shown in Figures 2 and 3;

Figures 5 and 6 are another embodiment of the present invention to be used as the upper portion of a gas lift in the system shown in Figure 1, Figure 5 being an elevation partially in section along the lines 5-5 in Figure 6 and Figure 6 being a top view.

In Figure 1 is shown a typical embodiment of the type of system with which the present invention is concerned. Since the invention is directed primarily to the upflow portion of the system and since the operation and construction of the reactor and regenerator or kiln of the typical system

shown in Figure 1 are adequately described in the afore-mentioned article appearing in the "Oil and Gas Journal," detailed illustration and description of the latter have been omitted for the sake of brevity. It is to be understood that various arrangements of kiln and reactor may be employed in connection with the present invention, as for example arrangements shown in the "Houdry Pioneer," vol. 1, February 1950.

As indicated in part by the labelled portions of Figure 1, relatively large particles of solid cracking catalyst, such as particles of between about 1 to 15 and preferably about 2 to 8 millimeters in diameter, flow downwardly through a reactor or cracking zone as a downwardly moving compact non-turbulent bed and contact hydrocarbons with the resultant formation of cracked products (synthetic crude) and are transferred through a conduit or seal leg to a regenerator, kiln or regenerating zone in which the coke deposited on the articles of catalyst in the cracking zone is removed. Compositions effective as hydrocarbon cracking catalysts (typically natural or synthetic aluminosilicates) and the conditions in the reactor and kiln are well known to the art and need not be repeated here.

Catalyst particles are withdrawn from the regenerator and flow downwardly in a conduit as a compact non-turbulent column to a gas lift inlet chamber, or particle supply hopper 10 surrounding the bottom of a gas lift, and are transported or lifted vertically upward as a continuous stream of solid particles by a gas introduced at a substantial pressure, such as from about 1 to 10 pounds per square inch gauge, to inlet chamber 10 by conduit 11 and/or 12. The gas used in lifting may be one derived from or one used later in the system, such as flue gas or hydrocarbon charge stock, either in liquid or vapor phase, respectively; or may be one used only for lifting, such as air or steam. The particles of contact material pass upwardly through a vertical cylindrical passageway, path, pipe or conduit indicated generally by 13 which provides a vertically elongated lifting zone to a closed vessel, hopper or separator 14 surrounding the top of lift 13, which vessel comprises a confined gas-solids disengaging zone. The disengaged lifting gas is thereafter removed from vessel 14, as from the top thereof by conduit 15.

Particles of catalyst disengaged from the lifting gas settle on the surface of a bed in vessel 14, from which bed the particles flow through a conduit or seal leg as a relatively compact non-turbulent column of particles to the reactor. It is to be understood that a particular type of separator, such as vessel 14, is not a part of this invention and that separators other than the one illustrated, which perform the function of separating the elevating gas and particles of catalyst by various specific methods, may be employed. Indeed, the gas, after disengagement from the particles of catalyst at the top of the lift path may, if desired, be passed downwardly through the bed of catalyst in the separator (as, for example, where hydrocarbons are employed as the lifting medium and cracking, in addition to that occurring in the lift, is desired), the lifting gas being finally disengaged from particles of catalyst at the bottom of the bed in vessel 14. At any event vessel 14 is of considerably greater horizontal cross sectional area than that of the top of lift path or conduit 13 such as from 25 to 100 times the area of the circle circumscribing the top of the gas lift 13 so that the par-

ticles spraying or fountainizing out of the lift pipe do not impinge against the walls. Also, when free settling of the particles emerging from the gas lift is employed as a means of separating the particles and lifting gas, the distance of the top of vessel 14 above that of lift pipe 13 should be great enough that there is little or no impact of the particles against the top of the disengaging hopper. Thus, for example, a distance of about 10 to 35 feet can be employed when the catalyst particles emerge with an average velocity of 20 feet per second from lifts of 12 to 20 inches in diameter.

In accordance with the embodiment of the present invention shown in Figures 2 and 3, the major and lower portion of the gas lift 13a has a constant circular horizontal cross sectional area while the upper and minor portion of the gas lift 13b is equipped with radial projections or chambers 16 which are placed or disposed at the periphery of the lifting zone or conduit 13b. Radial projections or chambers 16 are laterally confined at their outermost boundaries by outer walls 17, each of which tapers outwardly toward the top of conduit 13b along its complete vertical extent. Additional lateral confinement is provided by side walls 18. Radial projections or chambers 16 communicate unobstructedly along their complete vertical extent with the interior of lifting zone or conduit 13. In the embodiment of the present invention shown in Figures 2 and 3, the lift pipe proper (i.e., conduit 13b exclusive of the radial projections) has the same diameter in the upper portion 13b as in the lower portion 13a and the radial projections are channels that are rectilinear in horizontal cross sectional area.

In the modification shown in Figure 4, the radial projections or chambers are in the form of grooves 21 having straight radial side walls 19 and arcuate outermost boundaries 22 that are concave in respect to the interior of conduit 13b. As shown in Figure 4, conduit 13b has been modified between adjacent chambers to provide arcuate surfaces that convex to the interior of the conduit.

The same type of radial projections or chambers 16 as in Figures 2 and 3 are employed in the embodiment shown in Figures 5 and 6 but the upper portion of conduit 13b, exclusive of chambers 16, has been modified so that it tapers inwardly thereby having a frusto-conical shape tapering inwardly toward the top of the lift.

Although the modifications shown employ a straight line, the taper may follow a curve so that the radial projections are somewhat trumpet shaped.

The gas lifts shown in the drawings are operated by moving upwardly through the lower portion of the lifting zone or conduit a stream of lifting gas and particles at a substantial velocity. This stream has a constant, continuous circular flow area until it reaches the upper portion of the lifting zone or conduit 13b. Because the radial projections or chambers 16 communicate unobstructedly with the upper portion of lifting zone or conduit 13b, the outer portions of the stream of lifting gas and particles will flow radially outwardly in each of the chambers while the stream including the radially disposed portions in chambers 16 continues to move generally upwardly. In the embodiment shown in Figures 2 and 3, the lifting zone or conduit proper has a constant circular cross sectional area for the whole of its vertical extent and consequently the radial pro-

jections or chambers provide additional flow area for the stream as a whole. Depending upon the size relationship between the additional area provided by the radial projections of the conduit 5 and the area of the lift conduit proper (i.e., the circular portion of conduit 13, exclusive of the radial projections), the velocity of the stream of gas and particles as a whole can be accelerated, maintained constant or decelerated to any desired extent. Thus when relatively small angles of taper are employed (the angle of taper is measured as the inclination of side wall 17 to the vertical axis of the lift conduit), such as from 10 to 15 degrees of taper extending over relatively long upper sections, such as from about 10 to 30 feet, are used, the velocity may remain constant or be slowed down to a minor extent such as from 5 to 20 percent. When relatively sharp angles of taper such as from 10 to 30 degrees 15 extending over a relatively short portion of the lift path, such as from about 2 to 5 feet, the particles can be decelerated more rapidly, such as from 10 to 60 percent. The term, lift path, as used herein, is applied to the path extending from the bottom to the top of conduit 13.

In the embodiment shown in Figures 5 and 6, the velocity of particles in the upper portion of the lift pipe may be slightly decreased, remain constant, or increase depending upon the 20 relationship of the cross sectional flow area of the lift pipe below the radial projections and that of the complete flow area at the top of the lift pipe. This embodiment has the additional advantage, gained by gradually decreasing the central flow area of the lift path as the 25 stream moves upwardly in the upper portion 13b, of tending to force or urge a relatively large portion of the particles into the radial projections. This decrease in central flow area has the 30 further advantage of decreasing the diameter of the jet issuing from the top of the lifting zone, thereby diminishing the extent of jet action of the stream of particles, with a consequent decrease in the height necessary for free settling 35 of the emerging stream of particles.

It will be noted that, in all of the embodiments shown, the particles emerge from the end of the lifting zone or conduit, disposed over a greater area than the area through which they 40 are flowing (i.e., the circle circumscribing the outermost portion of the lift conduit is considerably greater than the area at the top of the conduit available for the flow of granular material and lifting medium), thereby effecting a dispersion of the particles before they enter 45 the disengaging zone or hopper. Consequently the density or concentration of particles in the portion of the disengaging zone immediately above the lift path is less with a resultant diminished tendency of the particles to form a 50 "mushroom" or cloud and/or to be broken by impact with other particles. Moreover, by providing a plurality of radial streams, the average distance of lateral travel of particles out of the stream of lifting medium is diminished so 55 that, averagely, the particles can begin to decelerate at earlier time or lower height than if they were concentrated in a single stream of relatively large cross sectional area.

An important advantage of the use of radial streams is that particles moving laterally out of the stream of particles and lifting medium (as defined by the top of the lift path) for subsequent settling do so with a minimum of collision with other particles. This effect is in

considerable contrast to a lift path of equal continuous circular cross section when the particles at the center must travel a considerable lateral distance before they can settle. The small lateral distance of travel with reduced collision provided by the present invention tends to reduce attrition and to result in a more stable operation of the gas lift.

It is to be understood that the present invention is applicable to a wide range of velocity conditions and particle concentration or density in the lifting zone. Various velocities and concentrations can be obtained by varying the amount and pressure of the lifting gas such as by controlling either the total or relative amounts of lift gas introduced by conduit 11 or 12. An effective range or particle concentration for commercial operation involving the size of particles referred to above is from about 0.5 to 20 percent of the apparent bulk density of the particles (i. e., the density of the packed mass of particles). For present commercial catalysts having apparent bulk densities of from about 40 to 55 pounds per cubic foot, average concentrations of about 1 to 7 pounds per cubic foot have proven particularly advantageous. Experience has shown that an advantageous range of particle velocities is about 30 to 100 feet per second (based on the average velocity of the particles at complete acceleration), although lower velocities, such as down to about 10 feet per second, may be employed generally in relatively short lifts such as those of 50 feet or less.

Obviously many modifications and variations of the invention as hereinbefore set forth may be made without departing from the spirit and scope thereof, and therefore only such limitations should be imposed as are indicated in the appended claims.

I claim as my invention:

1. Apparatus for elevating granular material through a vertical lift path by a fluid lifting medium comprising a disengaging chamber at the upper end of said lift path adapted to disengage said granular material from said lifting medium and a vertically elongated conduit defining said lift path and terminating in said chamber, the upper end portion of said conduit being gradually expanded radially along longitudinally elongated areas spaced uniformly around the periphery thereof, the expanded portions forming channels in communication with the central region of said conduit, said channels being of gradually increased cross-sectional flow area along their vertical extents to the top of said conduit.

2. The apparatus of claim 1 characterized in that the upper portions of said conduit between said expanded portions taper gradually inward.

3. The apparatus of claim 1 in which said expanded portions taper outwardly at an angle to the vertical of less than 5 degrees.

4. Apparatus for elevating granular material through a vertical lift path by a fluid lifting medium comprising a disengaging chamber at the upper end of said lift path adapted to disengage said granular material from said lifting medium and a vertically elongated conduit defining said lift path and terminating in said chamber, the upper portion of said conduit having a plurality of vertically elongated channels spaced around the periphery thereof, said channels being in communication with said conduit and rectilinear in horizontal cross section, said channels tapering outwardly along their vertical extents to the top of said conduit whereby the horizontal area circumscribing the top of said conduit is substantially greater than the horizontal area at the top of said conduit available for the flow of granular material and lifting medium therethrough.

5. Apparatus for elevating granular material through a vertical lift path by a fluid lifting medium comprising a disengaging chamber at the upper end of said lift path adapted to disengage said granular material from said lifting medium and a vertically elongated conduit defining said lift path and terminating in said chamber, the upper portion of said conduit having a plurality of vertically elongated grooves spaced around the periphery thereof, said grooves being in communication with said conduit and V-shaped in horizontal cross section with arcuate outer boundaries, said grooves tapering outwardly along their vertical extents to the top of said conduit whereby the horizontal area circumscribing the top of said conduit is substantially greater than the horizontal area at the top of said conduit available for the flow of granular material and lifting medium therethrough.
